(57) **CLAIM**

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with graphical user interface; showing the first embodiment of our new design;

FIG. 2 is a front view of a display screen with graphical user interface; showing the second embodiment of our new design;

FIG. 3 is a front view of a display screen with graphical user interface; showing the third embodiment of our new design;

FIG. 4 is a front view of a display screen with graphical user interface; showing the fourth embodiment of our new design;

FIG. 5 is a front view of a display screen with graphical user interface; showing the fifth embodiment of our new design;

FIG. 6 is a front view of a display screen with graphical user interface; showing the sixth embodiment of our new design;

FIG. 7 is a front view of a display screen with graphical user interface; showing the seventh embodiment of our new design;

FIG. 8 is a front view of a display screen with graphical user interface; showing the eighth embodiment of our new design;

FIG. 9 is a front view of a display screen with graphical user interface; showing the ninth embodiment of our new design; and,

FIG. 10 is a front view of a display screen with graphical user interface; showing the tenth embodiment of our new design.

The broken lines show a display screen or portion thereof, and form no part of the claimed design.
